William Burnet, Cincinnati, Hamilton Co. Ohio
Letters Patent No 392 Dated July 8th 1857

The Schedule referred to in these Letters Patent and making part of the same
To all whom it may concern.

Be it known that I, William Burnet, of
Cincinnati in the County of Hamilton and State of Ohio, have in
vented a new ornamental design for water coolers, and I do hereby

declare that the following is a full, clear, and exact description of the same, reference being had to the accompanying drawings forming part of this specification in which,

Fig 1 is a front elevation

Fig 2 is a side or edge view of the handle of the cover

Fig 3 is a side view of the ornament forming the spout.

Similar letters of reference indicate corresponding parts in each of the several Figs.

The outer casing of the cooler is of sheet metal in the form of a fluted column having a base and capital. The flutes a a are arranged similarly to those in the Ionic and Corinthian orders with fillets B B between them. The base consists of a fillet C surmounted by a cymatium d having conges e and f above and below it. The capital consists of a conge g surmounted by a cyma reversa h.

The spout I which receives the cock, represents a dolphin the cock being inserted in the mouth.

The cover is in the form of a cone whose apex is very obtuse. Its handle is formed by two dolphins j j united by a bunch of leaved scroll work K.

What I claim as my design and desire to secure by Letters Patent is 1st The form and general configuration of the outer casing substantially as described and represented in the drawings.

2nd The Dolphin spout I and

3rd The configuration of the handle j j K of the cover substantially as shown
